REFRIGERATOR

Aage B. Salto, New York, N. Y., assignor to Rex Cole, Inc., New York, N. Y., a corporation of New York

Application July 21, 1931. Serial No. 552,219

7 Claims. (Cl. 62—1)

The present invention relates to refrigerators and is more particularly directed toward a refrigerator employing a more or less toxic or irritant refrigerant and provided with a specific protective medium whereby the escape of such refrigerant into the open air is effectively prevented.

Many refrigerators employ sulphur dioxide as the refrigerating medium and, on account of the irritant and toxic properties of sulphur dioxide gas, the fire department regulations of many cities forbid the use of such refrigerators under certain conditions.

The present invention contemplates the provision of a refrigerator with suitable protective medium whereby the refrigerant such as sulphur dioxide is adsorbed by an adsorbent so that it cannot escape to the open air. The preferred material for this purpose is partially dehydrated aluminum trihydrate, known as "activated alumina".

The present invention is particularly well adapted for use in connection with water coolers and the like where the evaporator is not exposed to the open air, and to refrigerators of the type which employ a sealed-in motor and compressor with no exposed moving parts and requiring no extraneous oiling or upkeep, for with these refrigerators it is possible to completely enclose the condenser in a casing and to surround this unit with the adsorbent material.

The accompanying drawing shows a common form of electrically operated water cooler of the above type provided with the protective adsorbing medium, it being understood that the drawing is illustrative and that the invention is not limited to the form of refrigerator shown therein.

In the refrigerator illustrated, the entire refrigerating plant except the controls is enclosed within a steel shell or casing 10 of the usual type. The direction of flow of refrigerant is shown by the plain arrows, and of water by feathered arrows. The high pressure side of the refrigerator is placed below a partition 11 made of rigid insulating material as usual, while the low pressure side of the refrigerator is placed above this partition.

In the drawing, the refrigerating unit is shown at 12. This unit includes the totally enclosed motor and compressor. The double walled condenser tubes for carrying water and refrigerant are indicated at 13. They are enclosed in an oil bath 14. The float chamber is indicated at 15. The thermostat 16 is connected to a tube 17 which leads to a condenser cooling water valve 18 ex-

terior of the casing 10. This valve 18 is connected to the water tube of the condenser cooling coil 13 by a tube 19. The bottom of the casing 10 is closed off by a steel partition 20, welded or otherwise secured to the casing walls. Drain outlets 21, 22, and 23 are provided below this partition for draining the cooling compartments and cooling coil, as usual.

The upper compartment houses the usual low pressure part of the water cooler, and the top of the casing 10 supports a removable cooler top 30 generally made of porcelain and provided with the usual bubbler 31 and compartment 32 for the electrical control 33 for the motor.

The liquid refrigerant tube 34 extends from the float chamber 15 to the evaporator 35 carried in the upper compartment, and the gaseous refrigerant returns through the tube 36. The cooling water enters at 37 part of it passing through the cooling coils 15 and out through a tube 38 to the waste pipe 39. Fresh water also passes from the supply pipe 37 through the double walled pre-cooling coil 40, then through a water inlet tube 41 to the outer shell 42 of the cooling compartment. It then passes through the pressure regulator 43 and into the tank formed in the evaporator 35, from which it may be withdrawn through the tubes 44 and 45 to supply the bubbler 31, a remote bubbler connection 46, or otherwise. Waste water from the bubbler passes through the inner coils of the pre-cooler 40 and to the waste pipe 37.

The foregoing description relates in general to a well known water cooler now available, and the present invention relates to protecting the high and low pressure sides of refrigerators of this and other types, particularly those employing sulphur dioxide as a refrigerant.

The lower compartment housing the motor, compressor, condenser and associated parts, is completely closed and these parts are enclosed in a packing of the partially dehydrated aluminum trihydrate as indicated at A. This material of granular form is packed around all the various parts containing the sulphur dioxide. This material adsorbs 15% of its own weight of SO_2 gas and hence about 40 pounds of the activated alumina will suffice to provide an excess of adsorbent material for the six pounds of gas used in an ordinary water cooler. This construction affords a triple protection against the escape of SO_2 gas. First, the inner mechanism is sealed in steel, second there is a protective packing of the activated alumina, and third there is an outer casing of steel which requires com-

plete diffusion of any escaping gases so that all such gases will come in contact with the adsorbent. Before the gas can escape it must expel the air and build up a pressure in excess of 3 atmospheric.

The spaces about the low pressure side of the refrigerator are filled with this adsorbing medium as indicated at B where it affords all the advantages above referred to and functions as 10 an insulator about the evaporator to insure the cooling of the water.

It will, of course, be understood that the invention is not limited to water coolers having both high and low pressure units in one casing, 15 for it may be applied generally to evaporators which can be isolated from the outside air and to sealed-in motor compressor mechanism having no exposed moving parts and requiring no extraneous oiling or upkeep.

20 It is obvious that the invention may be embodied in many forms and constructions, and I wish it to be understood that the particular form shown is but one of the many forms. Various modifications and changes being possible, I do not otherwise limit myself in any way with respect thereto.

What is claimed is:

1. In a refrigerator employing a toxic refrigerating medium, the combination with the evaporator thereof, of an enclosing casing for the evaporator and a protective packing in the casing and about the evaporator, said packing comprising partially dehydrated aluminum trihydrate and being adapted to act as a specific adsorbing medium for any refrigerant which may escape.

2. In a refrigerator employing a toxic refrigerating medium, the combination with the con-

denser thereof, of an enclosing casing for the condenser and a protective packing in the casing and about the condenser, said packing comprising partially dehydrated aluminum trihydrate and being adapted to act as a specific adsorbing medium for any refrigerant which may escape. 30

3. In a refrigerator employing a toxic refrigerating medium, the combination with the condenser and evaporator thereof, of enclosing casings for the condenser and the evaporator, protective packing in each casing and about the condenser and evaporator, said packing comprising partially dehydrated aluminum trihydrate and being adapted to act as a specific adsorbing medium for any refrigerant which may escape. 35

4. In a refrigerator, the combination with a condenser containing sulphur dioxide as a refrigerant, of an enclosing casing containing partially dehydrated aluminum trihydrate in sufficient 95 amount to adsorb all the refrigerant.

5. In a refrigerator, the combination with an evaporator containing sulphur dioxide as a refrigerant, of an enclosing casing containing partially dehydrated aluminum trihydrate in sufficient 100 amount to adsorb all the refrigerant.

6. A refrigerator employing sulphur dioxide as a refrigerant and means to prevent the escape of such refrigerant to the surrounding air comprising an enclosing casing containing partially dehydrated aluminum trihydrate. 105

7. In a refrigerator the method of preventing the escape of substantial amounts of sulphur dioxide in the gaseous phase which consists in passing it through an adsorbent, in the form of 110 partially dehydrated aluminum trihydrate.
